FOUNDATION STRUCTURE

Thomas Richard Freeman, St. Louis, Mo.

Application January 26, 1945, Serial No. 574,647

15 Claims. (Cl. 61—51)

This invention relates generally to foundation structures for buildings and the like, and has particular reference to improvements in means and methods for raising foundations which have dropped or settled because of erosion or faulty sub-soil condition, for stabilizing foundations and the soil adjacent thereto to prevent slippage and settling, and for effecting lateral displacement or replacement of foundation walls and columns.

The present invention entails the hydraulic injection into the ground of a plastic, settable composition which functions to exert an elevating force on a wall, floor or column to be raised or stabilized, and to fill cracks and voids in and to harden the sub-soil for purposes of preventing erosion and soil-slippage in the regions about and under floors and footings.

The hydraulic injection of a filling material for soil stabilization purposes has heretofore been known and practiced, chiefly in connection with highway maintenance where the method is used for raising concrete paving slabs which have sunk below the normal grade. In the past several years the so-called mud-injection process has been employed, with indifferent results, for stabilizing the foundations of buildings and to prevent the further settling of buildings where such condition has been found to exist. In using the process for foundation stabilization the practice has been to bore a series of holes into the ground to a depth a substantial distance below the foundation footing, the series extending along the foundation wall, spaced to the outside of and away from the wall a distance of three or four feet. A mixture of mud and cement is then injected into the holes to fill voids and crevices caused by water erosion or the drying and shrinking of the soil, and, when possible, to compress the soil against the footing. The method has met with some success for the stated purpose where the faulty soil condition is not due to subterranean water erosion, but where such condition exists the described method cannot be relied upon. Although the raising of sunken paving slabs has for years been successfully practiced by injecting a mud composition below the slab, the described methods heretofore prevailing are not adapted to the raising of the foundations and walls of buildings. One reason for this is that the lifting forces cannot be localized or confined to the precise areas of the foundation where lift is desired, since the flowing mud may find a low resistance path and spread to other areas of the foundation, to exert a lifting force thereon at

a point where such would be damaging. Since by former methods it is impossible to maintain uniform the lifting forces at definite points along a foundation wall, there is produced internal stresses that tend to fracture the foundation and produce cracks in the masonry wall which it supports.

The chief object and purpose of the present invention is to provide a simple, inexpensive and highly satisfactory method for raising or restoring to an original location, foundation structures which have become displaced due to faulty sub-soil conditions, to stabilize such foundation structures and to effect a permanent support therefor so that they will remain in their normal or restored positions irrespective of shifts, slippage or erosion of the adjacent soil.

Several examples of means and methods for putting into practical effect the teachings of my invention are set forth in the following description, wherein reference is made to the accompanying drawing. In such drawing,

Fig. 1 is a sectional elevational view of a foundation wall, showing a vertical bore in the earth adjacent the wall, the provision of which bore constitutes an early step in the method;

Fig. 2 is a plan view showing the location and spaced arrangement of a plurality of bores along the foundation wall;

Fig. 3 is a sectional elevational view illustrating the lifting and supporting installation at a later stage in the method;

Fig. 4 is a sectional elevational view illustrating the manner in which the method of my invention is employed to produce lateral displacement or replacement of a foundation wall, and

Fig. 5 is a sectional view of the lower end of the bore, illustrating a fitting which is preferably employed to facilitate the method.

Describing now the means and method of my invention in detail, reference numeral 10 designates a concrete foundation wall having the customary footing 11. Closely adjacent to the foundation and preferably located at the outer side thereof so as to clear the footing, there is formed a vertical bore 12 which may be produced by a hand or power-driven earth auger known and available to the trade. The bore 12 extends downwardly below the footing 11 to a depth which will be determined by the character of the sub-soil. Where possible the bore 10 should extend downwardly to a rock or other strata which will assure permanently fixed anchorage and support for the structure. For most installations a bore eight inches in diameter has

been found suitable. Where a wall or other extended structure is to be raised or stabilized a series of such bores suitably spaced along the wall are provided as shown in Fig. 2.

After the bore or bores 12 have been drilled the auger is removed and a cut is made in the side of each bore to produce a cavity 13 immediately below the foundation footing 11, a suitable tool having an off-set digging head being employed for this purpose.

Thereafter, a length of pipe 14 is inserted vertically in and centrally of the bore as shown in Fig. 3, such pipe being of sufficient length to extend from the bottom of the bore to a point above the ground level, the pipe having a joint located a short distance below the ground level and the sections being connected together by a threaded sleeve coupling or pipe nipple 15. The upper pipe section, designated 14' is provided at its upper end with an elbow joint fitting 16 to facilitate connection with a pumping device, and with a cut-off valve 17 the purposes for which will also be subsequently explained. At its lower end pipe 14 is preferably provided with a dished or bell-shaped flange-like fitting 18, screw-threaded thereto. This member is of diameter slightly less than that of the bore to facilitate placing it at the bottom thereof, and serves to centralize the lower end of the pipe in the bore. Flange 18 serves the further important function of holding the pipe end out of contact with bottom of the hole, which otherwise would tend to obstruct the egress of mud or other composition employed in the process in the manner to be hereinafter explained. Although the size of the pipe 14 is not critical, a two inch diameter pipe has been found to be well suited for use where the bore is eight inches in diameter as heretofore recommended, such size permitting the plastic composition to flow therethrough without undue restriction, and in other respects adequately fulfills the purpose of reinforcing the column to be cast around it. Suitable reinforcing means in the offset cavity 13 are provided, desirably consisting of appropriately bent pieces 19 of steel reinforcing rod which may be initially held in place by securement to the pipe 14 as by wire ties or the like.

The space around the pipe 14 within the bore 12, and the cavity 13 is filled with cement, as appears in Fig. 3, the cement filling extending upwardly to a point above the foundation footing and preferably below the ground level. Before proceeding further the cement is allowed to set. There is thus produced a concrete column 20, having an integral, reinforced corbel or bracket 21 subjacent the foundation footing, the column being reinforced by the pipe 14 which also serves to provide a central fluid passage that extends longitudinally completely therethrough.

The described installation is now ready for the lifting and stabilizing phases of the process. These are carried out by injecting, by suitable pumping apparatus, a plastic, hard-setting composition into the upper end of pipe 14. Such an apparatus, indicated generally at 21 in Fig. 3, is known in the trade as a mud-jack. Its particular construction does not comprise a part of the present invention and any suitable hydraulic apparatus adapted to exert sufficient pressure on the plastic composition to cause it to flow through the column 20 will serve the purpose. The device illustrated may briefly be described for purposes of completeness as including a hopper 22, the bottom of which slopes toward one end and there communicates with a pumping chamber or cyl-

inder 23 containing a reciprocating power-driven piston or plunger 24. The pumping chamber discharges into a horizontal pipe section 25 which is connected to the cut-off valve 17 and through that member to the pipe section 14'.

A composition found suitable for injection into and through the column is made by mixing loose top soil or silty loam, comparatively free from sand, with water to form a thin mud. A small percentage of cement (about 5%) is added for setting purposes and to reduce shrinkage of the mud.

This composition is injected into the pipe 14 with sufficient pressure to cause it to flow through and out of the lower end of the column. The mixture is thus caused to fill all voids and fissures which may exist in the vicinity of the base of the column. After such openings have been filled, by continued pumping the hydraulic pressure on the lower end of the column exerts a lifting force which gradually raises the column, and with it the foundation resting on the bracket portion 21. When the structure has been raised to the desired level the valve 17 is closed so as to trap and confine the mud composition under pressure within and below the column. Following the elapse of sufficient time to allow the mud composition to harden the pipe section 14' is disconnected at the joint 15 and removed from the column; thereafter, the cavity remaining above the column is filled with soil up to the ground level.

Where a foundation wall is to be raised by the described process by means of a series of columns in the manner suggested by Fig. 2, suitable transverse piping 28 is provided to connect the upper ends of all of the column passages, and the mud composition is pumped through the columns simultaneously, so that equal lifting forces and uniform upward displacement of the columns will result. A valve 29 serves to maintain the mud composition under pressure during the setting period.

It will be understood that the mud composition spreads outwardly from or at the lower ends of the columns and produces an effective base or footing for these supports. It will further appear that the lifting forces on the foundation structure are definitely confined to the bearing areas afforded by the bracket portions 21 and the operator is in full and complete control of the acting forces, in degree and points of application.

The method for effecting lateral displacement of a wall or other support 29 is illustrated in Fig. 4 and in general accords with the method previously described. In this case an opening 30 of size sufficient to receive a workman is made in the ground adjacent the supporting structure to the depth of the base thereof. Next, a horizontal bore 31 leading from the opening 30 is made by suitable boring tools. Piping 32 and 33 leading from the base end of the bore to a valve 34 and a mud-jack is installed, and the bore 31 is filled about the pipe 32 with concrete to provide a strut member 35, as shown. Thereafter, mud composition is pumped through the piping to effect displacement of the concrete strut 35 and foundation structure 29 in the manner explained in connection with Figure 3. Where a foundation member of substantial depth is encountered, requiring lateral displacement, the provision of additional horizontal concrete struts located at varying levels below the grade, is recommended in order to reduce bending stresses in the foundation. In such case the fluid passages through the struts are interconnected by suitable piping

as suggested by Fig. 2, and the struts are pumped simultaneously in the manner and for the purpose heretofore mentioned.

I have described my invention with reference to several examples setting forth preferred methods of putting it into practical use. It will be understood that the invention is not confined to the particular methods and uses described herein, and is not intended to be so limited.

What I claim and desire to secure by Letters Patent is:

1. The method of raising and stabilizing a building foundation which comprises installing a hollow column vertically in the earth in supporting relation to the building foundation, forcing firm-setting fluid material through and out of the lower end of said column to elevate said column and foundation by the hydraulic pressure at the lower end of said column, and allowing said material to set while maintained under pressure.

2. The method of shoring a building foundation which comprises installing a hollow, open-ended column reaching downwardly to a substantially unyielding sub-strata of the earth, in supporting relation to said foundation, forcing firm-setting fluid material into and through said column until hydraulic pressure at the lower end is sufficient to raise the column, and maintaining said pressure while said fluid sets.

3. The method of shoring a building foundation which comprises installing a hollow, open-ended column in the earth adjacent said foundation and in supporting relation thereto, with the open lower end of said column reaching downwardly to a substantially unyielding sub-strata of the earth, forcing a firm-setting fluid material through and out of the lower end of said column until hydraulic pressure at said lower end is sufficient to raise the column, and maintaining said hydraulic pressure during the setting of said material.

4. The method of shoring a foundation structure which comprises forming in the earth in supporting relation to said foundation a concrete column having a fluid passage extending longitudinally therethrough, forcing a firm-setting fluid material through said passage to produce hydraulic pressure at the lower end sufficient to raise said column, and thereafter closing said passage to maintain said pressure during the setting of said material.

5. The method of shoring a foundation which comprises forming in the earth adjacent the structure a hollow, open-ended concrete column having a portion thereof extending underneath said structure, forcing firm-setting fluid material into the upper end, through, and out of the lower end of said column, and continuing the introduction of said material until hydraulic pressure at the lower end is sufficient to raise said column, and thereafter maintaining said pressure on the material during the setting thereof.

6. The method of raising a foundation structure which comprises forming in the earth adjacent said foundation a concrete column having a longitudinal fluid passage, and an integral bracket portion extending subjacent to said foundation structure, filling said passage with firm-setting fluid material, forcing additional of said material into said passage at its upper end so as to create hydraulic pressure on the lower end of said column sufficient to raise the column and foundation structure therewith, and thereafter closing off said passage at its upper end

whereby to maintain said pressure during the setting of said material.

7. The method of raising a foundation structure which comprises forming a bore in the earth adjacent said structure, excavating the earth below said structure to form a cavity communicating laterally with said bore, inserting a tubular reinforcing member longitudinally within the bore, filling said bore about said member and 10 said cavity with concrete, and allowing said concrete to harden to produce a supporting column, forcing firm-setting fluid material through and out of the lower end of said tubular member whereby to effect a raising of said column and foundation structure by hydraulic pressure at 15 the lower end of the column, and allowing said material to set while subjected to said pressure.

8. The method of shoring and stabilizing a foundation structure which comprises installing a plurality of columns having longitudinal passages therethrough in the earth, in supporting relation to the foundation structure and spaced therealong, pumping firm-setting fluid material through said columns, simultaneously and at uniform 20 pressure, whereby to provide uniform hydraulic pressure at the lower ends, sufficient to raise said columns, and maintaining said pressures during the setting of said fluid material.

9. The herein described method of raising and 30 stabilizing a foundation structure which comprises installing a plurality of columns having longitudinal, interconnected fluid passages therethrough, in supporting relation to and spaced along the foundation structure, pumping firm-setting fluid material into said passages whereby to produce uniform hydraulic pressure at the lower ends sufficient to raise said columns simultaneously, and allowing said material to set while subjected to said pressure.

10. The herein described method of raising a foundation structure which comprises forming a series of vertical bores in the earth, adjacent to and spaced along said foundation, excavating the earth at the sides of said bores to form cavities 45 immediately below the foundation, inserting lengths of pipe to extend longitudinally in said bores, substantially the full length thereof, filling the bores around said pipes and said cavities with cement and allowing said cement to set, pumping firm-setting fluid material through said pipes simultaneously, to produce uniform hydraulic pressure at the lower ends sufficient to raise said columns, and thereafter closing said passages to maintain said pressure while said material hardens.

11. The herein described method of raising a foundation which comprises forming a series of bores in the earth adjacent to and spaced along said foundation, excavating the earth at the sides 60 of said bores to form cavities subjacent the foundation, inserting pipes longitudinally within the bores, to extend substantially the full length thereof, inserting reinforcing means in said cavities, interconnecting said pipes, filling said bores around said pipes and said cavities with cement and allowing said cement to harden, pumping a firm setting fluid composition through said interconnected pipes, and out of the lower ends thereof, whereby to provide uniform hydraulic pressure at the lower ends of said columns sufficient to raise the same, and thereafter closing off said passages to maintain said pressure while said composition hardens.

12. The herein described method of moving a 70 previously formed foundation structure which

comprises forming a bore in the earth that extends away from said foundation, parallel to the direction in which said foundation is to be moved, disposing a pipe lengthwise in said bore, filling said bore around said pipe with concrete and allowing the concrete to harden whereby to form a hollow concrete strut, pumping a firm-setting fluid material through said strut to provide hydraulic pressure at the base of said strut sufficient to move the same longitudinally in the direction toward the foundation, and maintaining said pressure while said material hardens.

13. The method for moving a previously formed foundation structure which comprises forming a plurality of laterally spaced bores that extend from said foundation, parallel to the direction in which the foundation is to be moved, disposing pipes lengthwise in said bores, interconnecting said pipes, filling said bores around said pipes with cement and allowing said cement to harden, whereby to produce a plurality of hollow concrete struts, pumping firm-setting fluid material into and through the interconnected pipes whereby to provide uniform hydraulic pressure at the base ends of said struts, sufficient to move the same simultaneously in the direction toward the foundation, and thereafter maintaining said hydraulic pressure while said material hardens.

14. The herein described method for effecting lateral displacement of a previously formed foundation structure, which comprises forming a bore in the earth that extends substantially

at right angles to the foundation structure, disposing a pipe lengthwise in said bore, filling said bore around said pipe with concrete and allowing said concrete to harden whereby to form a hollow strut, pumping a fluid, firm-setting material through said strut to provide hydraulic pressure at the base end thereof sufficient to move said strut and the foundation therewith, and maintaining said pressure while said material hardens.

15. The herein described method for effecting lateral displacement of a previously formed foundation structure, which comprises excavating the earth to form a hole at one side of the foundation structure, extending to the base thereof, forming a bore in said earth extending from the bottom of said hole in a direction at right angles to the foundation structure, disposing a pipe lengthwise within said bore, substantially the full length thereof, filling said bore around said pipe, and the bottom of said hole with concrete and allowing said concrete to harden, whereby to produce a cast in situ hollow concrete strut, pumping a fluid, firm-setting material through said strut and out of the base end thereof, whereby to provide hydraulic pressure on the end of the strut sufficient to move it lengthwise in the direction toward the foundation structure, and thereafter maintaining said pressure while said material hardens.

30 THOMAS RICHARD FREEMAN.
